Attorney.

UNITED STATES PATENT OFFICE

WILLIAM F. HELMOND, OF WEST HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed April 23, 1923. Serial No. 272,052.

This invention relates mainly to the shift-frame bearings of typewriting machines.

Heretofore, difficulty and expense have been encountered in properly assembling a typewriting machine, at certain points where a fulcrum is required. This is particularly true in obtaining a proper adjustment of the platen lift-rail, which, for accurate alignment of the typed characters, must be parallel with the carriage way-rod. Formerly, due to variations in the machining of parts, it has often been necessary to assemble and disassemble several times the component parts of the lift-rail unit, until by successive slight adjustments the proper total adjustment has been consummated. What is true of the lift-rail and its proper adjustment is also true of other parts or units, such as the dog-rocker arm, tabulator, shift-lock, and lift-hooks.

It is an object of the present invention to overcome the above disadvantages, and to substitute a simple means whereby fulcrum adjustments may be easily, quickly, and permanently made.

A further object of this invention is to provide an off-center fulcrum that may withstand a lesser or greater torsional strain. Such withstanding of torsional strain is dependent on the amount of frictional resistance set up between the fixed bushing and the curved stem carrying the off-center fulcrum. This resistance can be varied by flattening or sharpening the curve or arc of the stem, or by decreasing or increasing its diameter.

In addition the stem may be tempered to decrease or increase its bow-spring quality. Finally, a combination of any or all of these methods may be employed.

The invention therefore relates to an improved means for providing an adjustable fulcrum, whereby the fulcrum can be set at various points in a line paralleling its axis, and also in a plane at right angles thereto. Furthermore, when said fulcrum has been adjusted and set in proper relation to some engaging member, the fulcrum and its component parts can be integrally removed and again be replaced in their housing, without

disturbing the aforementioned proper relation.

An object of this invention is to provide an adjustable fulcrum having few component parts, all of which are durable, and are easily and economically made and installed. Furthermore, a rotatable fulcrum-stud, as hereinafter described, can be utilized to take up wear on itself or in the engaging member, and without disturbing its bushing.

These improvements are particularly applicable to typewriting machines, but can readily and advantageously be incorporated in other mechanical constructions.

Other features and advantages will hereinafter appear.

In the accompanying drawings,

Figure 1 is a side elevation of a portion of a typewriting machine with the present invention applied thereto and showing the platen shifted to upper-case position.

Figure 2 is a plan view of the adjustable supporting mechanism, with the parts in section for showing the invention more clearly.

Figure 3 is a rear view showing the relation between the carriage-rails and the shift-rail and the adjustable supports for the latter rail.

Figure 4 is a perspective view of the bushing and the off-center stud together with its curved stem prior to being assembled.

Figure 5 is a similar view to Figure 4 but showing the parts assembled.

Figure 6 is a front diagrammatic view showing the platen shifted and supported by its shift-rail for typing with the upper-case characters.

Type-bars 10 are swung up to strike the platen 11 having a shaft 12 carried by end-plates 13 of a platen-frame 14 mounted for vertical movement in a carriage-frame 15 and guided in said vertical movement by the usual arms 16 and 17. The carriage is fed horizontally through the usual escapement-mechanism 18, and is guided by a front rail 19 and a rear rail 20 carried by a stationary main frame 21. The carriage is supported on the front rail 19 by a roller 22 suitably mounted on its front bar 23. The guiding

means at the rear of the carriage includes the rear rail 20, which is embraced by collars 24 fixed upon the rear bar 25 of the carriage. The platen 11 is supported in its lower or normal position by the end-plates 13 resting on the carriage-frame 15. For this purpose the plates are provided at their rear with flattened edges 26 to abut and rest on studs 27 forming part of the carriage, and are further supported at the front by extensions 28 of the plates 13 abutting the arms 29 of the carriage-frame 15.

The platen is shifted to its upper position by operation of the usual shift-key lever 30 causing its vertical arm 31 to rock a swinging frame 32 including a pair of pivotally mounted brackets 32^a fixed to the ends of a cross-shaft 33, and raise a guide-rail 34, which, in turn, through a roller 35, raises the platen-frame 14. The rail 34 is held in its raised or normal position by the usual holding mechanism shown in my Patent No. 1,223,279 of April 17, 1917, which includes a pivoted lever 36 carrying at its end an adjustable extension 37 provided with vertical slots 38 and 39. A pin 40 on the bracket 32^a enters either the slot 38 or 39, according to whether the rail 34 is moved to its lower or upper locked position.

When the rail is held in its upper position by means of the operator holding the shift-key down, the pin 40 remains in the position as shown in Figure 1; thus the rail is held firmly in its upper position. Since this rail 34, alone, forms the support and determines the position of the platen when the latter is held for movement horizontally in its upper-case position, it is desired to favor alignment of the typing line when both upper and lower case typing characters are typed, that the rail 34 be in perfect horizontal alignment with the carriage-rails 19 and 20 upon which the platen is directly supported in its lower position. For this purpose the brackets 32^a, together with the rail 34 fixed thereon, are adjustably supported for the trueing of said rail. The adjusting mechanism or unit includes a metal bushing 41, along the axis of which has been bored a hole 42. In hole 42 is placed a metal stem 43, having a tool head 44, at one end, substantially the same size as the diameter of the bushing. Said head 44 has its periphery cut with a plurality of faces, to be readily turned by a wrench. From head 44 there projects a bracket-supporting fulcrum stud or pin 45, set axially off-center from the stem or shank 43. The tool-head 44 is between the shank 43 and the stud, and can slip through the hole 46. Said stem is made to have a normally easy fit in the hole 42, but before insertion in the latter is bent or flexed slightly to assume an arc. Said arc constitutes a bow-spring, which, when forced into the bushing,

gives the stem a frictional resistance at several points along the walk of the hole 42, in bushing 41. Said resistance is anti-torsional, and is sufficient to prevent the stem from being turned by the weight or strain of the supported member. Said torsional movement is transmitted to the stem through the leverage set up by the supported member acting on the offset fulcrum-stud 45.

When assembled, the fulcrum-unit is placed in an opening 46 of the frame 21, as shown by Figure 3, and is moved axially to its proper position in said hole. While in such position, the bushing 41 is fixed by screwing in a set-screw 47. Said screw preferably has a flat end that abuts the flat cut-out 48, of the bushing 41, and holds said bushing against turning or sliding. When the bushing 41 has been thus properly fixed, the stem 43 is turned by its head 44, to bring the fulcrum-stud 45 to proper position in its radial plane for trueing the rail 34.

It will be apparent that, while stem 43 will not turn in its bushing 41 from a working strain applied to its fulcrum-stud 45, it can be turned by a greater force applied through its head 44. It is also obvious that once the stem 43 has been properly adjusted in the bushing 41, the whole unit may then be removed, without disturbing the relation of its component parts. In addition, the undisturbed unit may then be replaced at its exact previous location in the frame, and without changing the preadjusted relation between its fulcrum-stud and the supported member. This axial preadjusted location can be again reached, when the head 44 has abutted its supported member. Such axial location can also be gaged by an observance through the set-screw hole of any mark or depression left on the cut-out 48, by the set-screw 47, when the latter received its initial set. The set-screw also embodies another desired result. When it is threaded in to abut said cut-out, the resultant pressure of its end brings said cut-out into the same plane as previously occupied. The bushing thus having been correctly relocated, it follows that its component fulcrum-stud will also assume its pre-adjusted location in relation to its supported member.

It can readily be seen that the off-center support can be used for either both ends or only one end of the supported member, which would be determined by the amount of adjustment necessary for the rail 34. When the rail 34 is adjusted by movement of the bracket 32^a through its off-center support 45, the holding extension 37 has to be correspondingly adjusted on the lever 36 to bring the slots 38 and 39 into proper relation with the pin 40. For this purpose the extension is provided with a slot 49 through which a screw 50 extends, so that upon

loosening of the screw 50 the extension may be slidably adjusted to bring the slots 38 and 39 in proper registration with the pin 40. The extension 37 is further provided with 5 inwardly-extending lugs 51 for guiding and maintaining its proper relation on the lever 36 when it is slidably adjusted.

Variations may be resorted to within the scope of the invention, and portions of the 10 improvements may be used without others.

Having thus described my invention, I claim:

1. An adjustable supporting unit including a bushing having a circular opening and 15 an off-center pin having a normally flexed stem, press fitted in said opening so that the bushing is effective to straighten the stem and thereby tension the same to frictionally bind upon the wall of the opening.

20 2. An adjustable supporting unit including a bushing having a circular opening and an off-center pin having a normally flexed stem, press fitted in said opening so that the bushing is effective to straighten the 25 stem and thereby tension the same to frictionally bind upon the wall of the opening and hold said off-center pin in a fixed relative position to the bushing, the bushing being provided with means to determine its 30 fixed position when secured in a housing.

3. The combination with a supported member and a housing, of a unit rigidly mountable in the housing and including a bushing, and an adjustable off-center stud 35 carrying the supported member, said stud forming part of a head having a stem arranged in the bushing, said stem being normally flexed and press fitted into the bushing whereby the stem is held against 40 displacement from the bushing by its inherent resiliency.

4. The combination with a supported member and a housing, of a unit rigidly mountable in the housing and including a 45 bushing, and an adjustable off-center stud carrying the supported member, said stud forming part of a head having a stem arranged in the bushing, said stem being normally flexed and press fitted into the bush- 50 ing whereby the stem is frictionally held against displacement by virtue of its own resiliency, the head on said stem being provided with a gripping surface to enable a sufficient rotating force to be applied there- 55 to for overcoming said frictional resistance to adjust said off-center stud.

5. The combination with a supported member and a housing, of a unit rigidly mountable in the housing and including a 60 bushing, and an adjustable off-center stud carrying the supported member, said stud forming part of a head having a stem arranged in the bushing, said stem being normally flexed and press fitted into the bush- 65 ing whereby the stem is held against dis-

placement from the bushing by its inherent resiliency, said unit being held rigid to prevent it from sliding or rotating when placed in its housing by means of a holding screw threaded in said housing.

6. The combination with a supported member and a housing, of a unit rigidly mountable in the housing and including a bushing, and an adjustable off-center stud carrying the supported member, said stud forming part of a head having a stem arranged in the bushing, said stem being normally flexed and press fitted into the bushing whereby the stem is held against displacement from the bushing by its inherent resiliency, said unit being held rigid to prevent it from sliding or rotating when placed in its housing by means of a holding screw threaded in said housing, the bushing being provided with a flattened surface 70 against which a flattened end of said screw may bear for relocating said unit when it is replaced in its housing.

7. The combination with a supported member and a main frame, of a bushing removably fitted in said main frame, an off-center stud carrying the supported member, said stud being rotatable in said bushing and having means co-operative with said bushing for firmly holding the stud at different rotative adjustments in said bushing, said bushing with said adjusted stud being detachable as a unit, and means for mechanically re-locating and holding said bushing after detachment and replacement 75 thereof, and thereby preserving the adjustment of said stud.

8. The combination with a supported member and a main frame, of a bushing removably fitted in said main frame, an off-

center stud carrying the supported member, said stud being rotatable in said bushing and having means co-operative with said bushing for firmly holding the stud at different rotative adjustments in said bushing, said bushing with said adjusted stud being detachable as a unit, and means for mechanically re-locating and holding said bushing after detachment and replacement 100 thereof, and thereby preserving the adjustment of said stud, said main frame having a hole in which said bushing is fitted, and said stud having a shank rotatively fitted in said bushing, and having a tool-head between the shank and the stud; said hole being of sufficient diameter to permit the 105 passage of said tool-head.

WILLIAM F. HELMOND.
